FUEL RESERVOIR FOR OIL BURNING
HEATERS

Donald B. Tolley and Dewey H. Hill, Macomb,
Ill., assignors to Globe American Corporation,
Kokomo, Ind., a corporation

Application November 21, 1941, Serial No. 419,827

3 Claims. (Cl. 158—41)

This invention relates to the fuel reservoir for an oil burning heater including a portable tank and reservoir pan with cooperating parts applicable to an oil burning stove.

The purpose of this invention is to provide a fuel oil reservoir for the usual household oil stove which will be convenient to handle in respect to refilling. Whereas most fuel oil reservoirs mounted in connection with such stoves requires the fuel oil to be carried in a separate container from which it is poured into a tank, or wherein the reservoir includes a removable tank adapted to be filled away from the stove and set into place in a reservoir pan after filling which is difficult and inconvenient, it is the purpose here to so construct and arrange the tank and reservoir pan that the tank may be readily and conveniently removed from the side of the stove with a minimum of effort and inconvenience.

Thus, in the present invention the oil burning stove is provided with a fixed reservoir pan provided with supporting slide members on each side thereof spaced from the bottom upon which the portable reservoir tank rests when in place and is slidably supported and guided to permit it to be removed and replaced laterally thereof, all as will hereinafter more fully appear.

Another feature of the invention consists in providing the bottom of the reservoir tank with a spring actuated control valve to be actuated by a raised formation in the bottom of the reservoir pan for opening said valve when the tank is placed therein and automatically closing it when raised for removing it.

Another feature resides in the provision on the bottom of the tank of guard devices such as will protect the valve structure against actuation or damage when the tank is removed while permitting its free actuation when the tank is placed in the reservoir.

The full nature of the invention will be understood from the accompanying drawing and the following description and claims:

Fig. 1 is a side elevation of the back portion of the stove with an end elevation of the reservoir, including the tank and the reservoir pan, with a portion thereof in section. Fig. 2 is a rear elevation of the reservoir and the lower portion of the stove with portions of the reservoir pan and control valve shown in section. Fig. 3 is a perspective view of the reservoir tank and pan with the tank partially removed therefrom. Fig. 4 is an enlarged view of the valve and cap structure.

In the drawing there is shown the outer cas- 55

ing 10 of an oil burning stove upon the rear side of which there is mounted a fuel oil reservoir having the usual oil line connection with the oil burning stove within the casing 10.

5 The fuel oil reservoir comprises a reservoir tank 11 seatable within a reservoir pan 12. Said pan is supported by a frame comprising the depending legs 13 which are secured to the housing 10 by the flanges 14.

Spaced downwardly from the upper edge of the pan and extending inwardly from and secured to the side walls thereof, there is a pair of oppositely disposed tank supporting and guiding shelves 15. Said shelves are so arranged as to receive and support the bottom of the tank 11 in spaced relation to the bottom of the pan and at the proper elevation therefrom to permit of the desired level of oil to be maintained therein. Also, said shelves are spaced downwardly from the upper edge of the pan sufficiently to position and maintain the tank therein while permitting of its ready removal through a sliding movement thereon in the manner shown in Fig. 3.

The tank is provided on at least one end with 25 a handle 16 adjacent the top thereof, which handle may be grasped for removing the tank. Its location adjacent the top thereof is important in that by reason thereof the tank may be lifted by the one handle while standing at one side of 30 the stove, and caused to slide endwise at its opposite end upon the shelves 15 in position to ride over the upper end edge of the pan until freed therefrom. Thereupon the tank may be carried to a refill station in an angular depending position. At the refill station the tank is inverted 35 so that the filler cap 17 is uppermost. Said filler cap may then be unscrewed and the tank filled.

The filler cap is provided with a spring actuated valve, as shown in Figs. 2 and 4, wherein 40 there is provided a valve head 18 for controlling the discharge orifice 19 in the cap. Said valve is provided with a normally downwardly extending plunger 20 and is maintained in closed position under spring tension by a spring 21 bearing against the valve and a spring retainer 22. For 45 protecting said plunger in the removal and handling of the tank a pair of bowed wire guards 23 are secured to the bottom of the tank in such manner as to extend to a position below the plunger on each side thereof. Thus, when the 50 tank is caused to slide over the end edge of the pan, as in Fig. 3, it will slide upon the guards 23 so as to carry the plunger free thereof and prevent contact. It is to be noted that when the

tank is raised for removal from the pan, the spring 21 will seat the valve 18 and close the opening in the cap 17.

After filling of the tank, it is replaced in the pan by first setting the lowermost end edge on the shelves 15 at the near end of the pan. Thereupon the tank may be caused to slide endwise on said shelves until it reaches the opposite end of the pan and is freed to be lowered into seated position. To permit thereof the guards 23 are so positioned and spaced that they ride inside of the shelves and do not engage therewith.

For controlling the valve through the plunger 20 the central position of the bottom of the pan is provided with a camming surface 24 extending upwardly into the path of the plunger, but between the guards 23 so as not to be engaged thereby. By means of this camming surface formed on the bottom of the pan, the valve 18 will be automatically opened when the tank is lowered into seated position, and automatically closed when the tank is raised from seated position for removal. When the valve is thus opened, oil is permitted to flow into the pan to a level controlled by the valve opening and be maintained at such level so long as any oil remains in the tank. The oil is fed in the usual manner from the bottom of the reservoir pan 12 through the feed line 25 through the valve control unit 26 and line 27 to the oil burner within the housing 10.

The invention claimed is:

1. A fuel oil reservoir for oil burning stoves comprising a tank supporting open top reservoir, a tank nested therein and having a single opening in the tank bottom for tank filling and fuel oil discharge purposes, a contact actuatable, normally closed valve in said opening, and guard means carried by the tank and depending therefrom and fully seated in the reservoir when the tank is nested therein and ineffective to prevent valve-reservoir contact when so nested for automatic tank discharge to said reservoir, the latter including therein ledges below but adjacent the top edge and at opposite sides thereof and directed inwardly towards each other providing a space therebetween, the tank when nested resting on said ledges and being tiltable relative thereto and fulcruming thereon, as well as slideable longitudinally thereof for removal, the contact actuatable valve having a contactable portion projecting below the tank bottom and positionable between the ledges when the tank is nested thereon, said guard means being of dual character, each being disposed between the valve and the adjacent supporting ledge to extend downwardly from and along the tank bottom having its lowermost portion in common alignment with the valve contactable portion, each guard means

being of skid-like character for reservoir top edge contact in tank removal and insertion from the reservoir for prevention of valve actuation and for valve protection.

2. A fuel oil reservoir for oil burning stoves comprising a tank supporting open top reservoir, a tank nested therein and having a single opening in the tank bottom for tank filling and fuel oil discharge purposes, a contact actuatable, normally closed valve in said opening, and guard means carried by the tank and depending therefrom and fully seated in the reservoir when the tank is nested therein and ineffective to prevent valve-reservoir contact when so nested for automatic tank discharge to said reservoir, the latter including therein ledges below but adjacent the top edge and at opposite sides thereof and directed inwardly towards each other providing a space therebetween, the tank when nested resting on said ledges and being tiltable relative thereto and fulcruming thereon as well as slideable longitudinally thereof for removal, the contact actuatable valve having a contactable portion projecting below the tank bottom and positionable between the ledges when the tank is nested thereon, said guard means being of dual character, each being disposed between the valve and the adjacent supporting ledge to extend downwardly from and along the tank bottom having its lowermost portion in common alignment with the valve contactable portion, each guard means being of skid-like character for reservoir top edge contact in tank removal and insertion from the reservoir for prevention of valve actuation and for valve protection.

3. A fuel oil reservoir structure for oil burning stoves comprising a tank supporting open top reservoir having an elevated contact portion, a tank adapted to be nested therein having a filling and discharge opening in its bottom aligned with said contact portion when in nested position, a closure for said opening having a normally closed contact actuatable valve movable to open position upon contact with said elevated portion, and guard members for said valve depending from the bottom of said tank to be fully seated in the reservoir when the tank is nested therein and spaced apart sufficiently to avoid said contact portion whereby said guard members are ineffective to prevent the contact actuatable normally closed valve from contacting the elevated contact portion when the tank is nested in said reservoir.
